Primary Examiner — Michael C Stout*Assistant Examiner* — Tia Ruth-Renee Polidori(74) *Attorney, Agent, or Firm* — Westbridge IP LLC(57) **CLAIM**

The ornamental design for a pellet stove, as shown and described.

DESCRIPTION

FIG. 1 is a front, right, top perspective view of a pellet stove showing our new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 2.

The dot-dash broken lines in FIGS. 1, 2, 9, and 10 depict partial view indicia that forms no part of the claimed design. The portions of the pellet stove shown in dash-dot broken lines form no part of the claimed design.

1 Claim, 10 Drawing Sheets(56)
